[57] CLAIM

The ornamental design for a coagulation characteristic testing instrument, as shown and described.

DESCRIPTION

FIG. 1 is a front, right, top perspective view of a coagulation characteristic testing instrument, showing our new design, with the testing strip portion outside of the instrument;
FIG. 2 is a top plan view thereof;
FIG. 3 is a bottom plan view thereof;
FIG. 4 is a right side elevational view thereof, with the left side elevational view being a mirror image thereof;
FIG. 5 is a front elevational view thereof;
FIG. 6 is a rear elevational view thereof; and,
FIG. 7 is a front, right, top perspective view thereof, with the testing strip shown inserted.
